INTERNAL COMBUSTION ENGINE

Karl L. Herrmann, South Bend, Ind.

Original application May 14, 1937, Serial No. 142,653. Divided and this application October 29, 1938, Serial No. 237,625

10 Claims. (Cl. 309—4)

This invention relates to internal combustion engines, and more particularly to combustion engines of the barrel type.

The present application is a division of my copending application, Serial No. 142,653, filed May 14, 1937.

The engine to which the present invention relates is of the type having its cylinders parallel to the axis of the engine, and the invention may be used with such inventions employing either a four stroke cycle, a two stroke cycle or a Diesel system. It is adaptable to engines for use in motor vehicles, aeroplanes, or in marine, railway or stationary engines.

One object of the present invention is to provide such an engine with power applying means that will run without vibration and which is smooth and quiet in operation, compact in size, light in weight, and more economical in the use of fuel, lubricant, and cost of maintenance per horse power developed than the conventional type of engines now in use.

One of the main features of the present invention is the provision of a double ended piston for this type of engine, which has a sufficiently flexible skirt so that the forces which result in sidewise pressure against the cylinder wall will be well distributed over the entire available bearing surface.

Another feature of the present invention is the provision of a bearing assembly which may be carried in the connecting portion of the double ended piston for transferring the piston thrust to the engine shaft as torque through the medium of a cam.

A further object is to provide a double ended piston that is light in weight, is rigid with its connecting member, and is designed to eliminate localized sidewise pressure against the cylinder wall and is so constructed as to have substantially uniform heat dissipation.

Still another feature of the present invention is the elimination of anti-friction bearings in the double ended piston for the roller members which impart the thrust of the piston to the cam to convert it into torque on the engine shaft.

Still another feature of the present invention is the provision of a piston construction in which the connecting portion between the two ends of the piston is so designed as to afford uniform pressure distribution to the cylinder wall, adequate lubrication of the bearing surfaces between the cam following rollers and the journals or bearing supports in the piston, and also provides adequate bearing support on the cam.

Still another advantage attained by the present invention is the provision of a double ended piston so constructed as to have sufficient strength to resist the lateral stresses to which it may be subjected, and yet which has a sufficiently flexible skirt portion so as to provide the proper sealing of the piston heads in the opposed cylinders with the central portion being of sufficient strength and rigidity to maintain the piston against distortion and absorb all lateral and tangential stresses while providing for proper transmission of thrust from the piston head to the cam carried by the engine shaft through which the torque is transmitted.

Another feature of the present invention lies in the provision of a crowned contact surface on the cam engaging roller, to prevent cramping which might occur due to flexure of parts or manufacturing tolerances or clearances.

Other objects and advantages of the present invention will appear more fully from the following detailed description, which, taken in conjunction with the accompanying drawings, will disclose to those skilled in the art the particular construction and operation of the preferred form of the present invention.

In the drawings:

Figure 1 is an elevational view partly in section of a barrel type engine embodying the present invention;

Figure 2 is an elevational view partly in section of a piston such as may be employed for the engine shown in Figure 1;

Figure 3 is a plan view of a modified form of piston;

Figure 4 is an elevational view, partly in section, of the piston shown in Figure 3;

Figure 5 is a sectional view taken substantially on line 5—5 of Figure 4;

Figure 6 is a sectional view taken substantially on line 6—6 of Figure 4;

Figure 7 is a sectional view taken on line 7—7 of Figure 4;

Figure 8 is a sectional view taken substantially on line 8—8 of Figure 4;

Figure 9 is a view showing in detail one of the cam followers in position in the piston; and

Figure 10 is an elevational view of the cam follower.

Considering now in detail the drawings, there is disclosed an internal combustion engine, indicated generally at 5, of the barrel type having twelve cylinders in two groups of six each. As shown in Figure 1, the engine is composed of two similar halves 6 and 7 bolted together as

indicated at 8 substantially centrally of the engine. The drive shaft 10 extends axially through both halves of the engine with the cylinders being equally spaced in a circle about the shaft. The drive shaft has mounted on it or formed integral with it an enlarged portion 11 disposed approximately midway between the ends of the shaft, this portion being positioned by the thrust bearings 12 bearing against perpendicular thrust surfaces 13 formed on the enlarged portion 11. Supported on and carried by the enlarged portion 11 is a T section driving cam 14 through which the driveshaft is driven from the pistons.

The shaft 10 extends the entire length of the engine and is provided with journal surfaces adjacent opposite ends thereof for holding the shaft in alignment. One end of the driveshaft may be provided with an ignition distributor (not shown) and the opposite end is arranged for coupling to any desired transmission mechanism. The cylinder block is formed in two sections 19 and 20 secured together by the bolts 8. Adjacent the ends of the cylinder block sections 19 and 20 are cylinder heads 24. Both the cylinder block sections and the cylinder heads are similar, and it is not believed that a detailed description thereof is necessary in describing the present invention.

On the head 24 there is secured a valve cover 25 and within the cover 25 are a plurality of valves such as indicated at 26, cooperating with valve openings 27 formed in the cylinder heads for communication with the respective cylinders disposed about the driveshaft. Each of the block halves 19 and 20 is provided with six cylinder bores, such as indicated at 28, and each cylinder bore has associated therewith a piston 29 of a double ended piston such as indicated generally at 30.

The double ended piston as shown more in detail in Figure 2, comprises a pair of pistons 29 and 32 connected by a connecting portion 33. The connecting portion has formed therewith a pair of journals 34 and 35 within which there are mounted roller bearings and cam followers such as 36 and 37, the cam followers contacting with the cam 14 and transforming the energy of the pistons into torque for rotating the shaft 10.

Each of the cylinders 28 is provided with a water jacket 40 surrounding the same for cooling the cylinders, and lubricant is supplied to the cylinders between the ends of the piston 30 by means of a series of spiral baffles 42 and 43 mounted on the drive shaft 10 and moving lubricant from a suitable reservoir axially in opposite directions along the shaft, a portion of this lubricant passing through the thrust bearings 12 and thence into the interior of the cylinder between the opposed pistons 29 and 32.

The design of the double ended pistons is a special feature of my invention, and one form of such design is clearly shown in Figure 2. The piston units comprise a pair of pistons 29 and 32 connected by a connecting portion 33. The connecting or center portion may be considered as a beam for transferring the load caused by the reciprocating compression and explosive forces to the skirts 92 of the piston heads. The beam in addition to supporting the follower rolls 36 and 37, transfers the loads well up into the skirts of the pistons. There the beam is secured to a rib 93 arranged transversely of the body portion of the piston and to a second rib 94

extending longitudinally of the piston but at right angles to the beam 33. This allows the expansion of the rigid rib and connects the beam through the ribs 93 and 94 to the semi-flexible skirt portion 92 of the piston head. As may be seen at 95, the piston head is slotted to allow for flexing thereof. The beam is preferably reinforced, as at 96, to stiffen the structure through the wear pads 99 bearing on the side 10 of the cam 14. The center portion of the beam 33 may be of U section, and the outboard bearing or wear pads 99 serve to prevent rotation of the pistons with respect to the cylinder bores.

Considering now the preferred form of piston shown in Figures 3 to 9, inclusive, a piston structure 60 is shown having the opposed piston heads 62 and 63. The skirt portions 64 and 65 respectively of the two pistons are slotted as indicated at 66 to provide for a semi-flexible connection between the heads and the skirt portions.

The two skirt portions 64 and 65 are connected by a central beam portion 67 which is arcuate in shape, as indicated in Figure 5, and which is provided with a central longitudinally slotted portion 68 for a purpose to be herein-after described. As shown clearly in Figure 5, the beam portion 67 of the piston terminates in an angled, slightly curved surface 69 at opposite sides of the piston which form wear pads bearing on the cam follower 14 to prevent rotation of the piston relative to the cylinder bores. In order to reduce the wear surface, the inner part of the beam 67 may be undercut to clear the cam follower 14, and thus to provide opposed wear surfaces 59. These surfaces prevent rotation of the piston in the cylinder, while the arcuate portion of the beam 67 transmits lateral thrusts directly to the cylinder wall, allowing reducing of the rib sections in the piston.

To provide rigidity of connection between the beam portion 67 and the piston skirts 64 and 65, the piston skirt is provided with a transverse re-enforced web portion 62 and with a longitudinally extending web portion 63 projecting at right angles to the web 62. This provides for a rigid positive connection between the beam portion and the opposed piston skirts with the slotted portions 66 providing the flexibility required for proper sealing of the piston heads in the cylinders. If desired to increase the strength and rigidity of the connecting beam 67, the cam follower rollers may be placed below the center of the piston, thus increasing the cross-section of the beam and also the lateral arcuate bearing surface between pads 59.

Below the slot 68 there is provided semi-cylindrical journal surfaces 64 which are in alignment with the opposite ends of the slot 68 and between which and the beam portion 67 of the piston there is a cut-back portion 65 adapted to receive the roller portions 66 of the cam followers, indicated generally at 67 in Figures 9 and 10. The cam follower 67 comprises a journal pin portion having the integrally formed cylindrical roller 67, the pin 68 having opposite trunnion or journal ends 69 and 70 adapted to be received in the ends 72 of the slot 68 and the semi-cylindrical journal portions 64 at the lower ends of the webs 62. It will be seen that with such a construction the rollers 66 which engage the cut-back portions 65 of the opposed piston skirts, while the pin 67 is journalled so that the opposed trunnion ends 69 and 70 thereof rotate in the semi-cylindrical journal portions 72 and 64 dis-

posed at opposite sides of the cut-back portion 65. This allows for insertion of the cam followers into position with the piston disposed in the cylinder and eliminates the necessity of roller bearings or the like such as are required in the piston construction shown in Figure 2. This also eliminates the necessity of lock rings and retainers for holding needle bearings in position, as required in the construction shown in Figure 2, and greatly facilitates the assembly of the cam followers in the pistons. The roller portions 66 may have spherical cam contact surfaces, if so desired, to prevent cramping due to flexure or manufacturing tolerances.

It will be apparent from an inspection of Figure 1 that the lubricant directed by the spiral baffle 42 along the shaft 10 and through the thrust bearing 12 and into that portion of the cylinder intermediate the pistons 29 and 32 or 52 and 53 will be thrown backwardly and forwardly upon reciprocation of the double-ended piston, and will be splashed against the lateral surfaces of the journal portions 69 and 70 of the pin 68 as well as on the cam surfaces of the cam 14. Inasmuch as the rollers 66 are pressed onto the pins 68 and must necessarily rotate as the cam 14 passes therethrough, it is obvious that this film of lubricant will be passed onto the surfaces 64 and 72 to insure adequate lubrication thereof without the necessity of using anti-friction bearings to journal the pins 68. Also, it will be noted that the cut-back portions 65 in the piston skirts are slightly greater than the diameters of the rollers 66, thus providing sufficient clearance to insure free movement of these rollers and also accommodating slight wear of the bearing surfaces 64 and 72 before the roller 66 will engage the surface of the cut-back portion 65.

I have found in experimentation that sufficient lubrication is provided on the journal surfaces 64 and 72 to prevent any appreciable wear thereof during a period substantially equivalent to the life of such an engine. If desired, bearing metal inserts, such as bronze or babbitt, might be provided for these surfaces or the metal might be hardened at these points if so desired.

It is therefore believed apparent that I have provided a novel type of double-ended piston which is very simple in design and assembly, which requires no complicated anti-friction bearing assembly, and which can be readily inspected and maintained in properly lubricated condition at all times.

The inventive features of the above described piston structures as an active part of an engine assembly forms the subject-matter of my co-pending application for Letters Patent of the United States for improvements in Internal combustion engine filed May 6, 1940, and serially numbered 333,519, the same being a division of the present application.

It is to be understood that the above-described embodiments of the invention are for the purposes of illustration only, and various changes may be made therein without departing from the scope and spirit of the invention.

I claim:

1. A double-ended piston having a longitudinally extending connecting beam portion, a longitudinal slot therein intermediate the pistons, a pair of semi-cylindrical bearings on the adjacent ends of the piston in line with the ends of the slot and forming spaced bearings with said slot ends.

2. The combination with the piston of claim 1

of trunnioned cam followers journaled directly in said spaced bearings.

3. A double-ended piston having a longitudinal connecting beam portion, a longitudinal slot therein defining at opposite ends semi-cylindrical bearing surfaces, transversely spaced bosses on the adjacent ends of the pistons having semi-cylindrical bearing surfaces alined with said slot surfaces, cam followers having trunnion ends journaled in each set of bearing surfaces, said trunnion ends being laterally exposed to receive lubricant therein from intermediate the pistons.

4. A double ended piston structure including end piston portions and an interconnecting strut portion, said strut portion having a slot therethrough extending longitudinally of said piston, the ends of said slots being formed to provide semi-cylindrical bearing surfaces, an additional semi-cylindrical bearing surface in axially aligned and axially spaced relation with respect to each of the first mentioned semi-cylindrical bearing surfaces, a roller received between the semi-cylindrical bearing surfaces at each end of said piston and trunnions for each said rollers journaled in the corresponding pair of said semi-cylindrical bearing surfaces at the corresponding end of said piston.

5. A piston comprising opposed piston-like end portions axially spaced from one another and an interconnecting portion integral with both said end portions, a pair of rollers each arranged with its axis approximately diametrically disposed with respect to said piston and spaced from each other axially thereof, each of said rollers having trunnions integral therewith and projecting axially from opposite sides thereof, and said piston having bearing surfaces open to reception of said trunnions during bodily movement of said rollers and trunnions axially of said piston.

6. A double ended piston comprising, in combination, a pair of axially spaced opposed end portions forming pistons and an interconnecting strut formed integrally with said end portion, said strut having an elongated slot therein provided with semi-cylindrical end surfaces the axes of which are arranged diametrically of said piston and which surfaces form bearing surfaces, and an additional pair of semi-cylindrical bearing surfaces carried by said piston each arranged in axial alignment with one of said semi-cylindrical surfaces at the ends of said slot and being spaced therefrom diametrically of said piston.

7. A double ended piston comprising, in combination, a pair of axially spaced opposed end portions forming pistons and an interconnecting strut formed integrally with said end portion, said strut having an elongated slot therein provided with semi-cylindrical end surfaces the axes of which are arranged diametrically of said piston and which surfaces form bearing surfaces, an additional pair of semi-cylindrical bearing surfaces carried by said piston each arranged in axial alignment with one of said semi-cylindrical surfaces at the ends of said slot and being spaced therefrom diametrically of said piston, a roller interposed between and substantially bridging the space between each pair of said bearing surfaces at the corresponding end of said piston, and trunnions integral with said rollers and received by said bearing surfaces.

8. In combination, a double ended piston formed to provide both laterally and longitudinally spaced semi-cylindrical bearing surfaces between the ends thereof, a cam having a rim portion interposed between the longitudinally

spaced bearing surfaces, and anti-friction members interposed between said cam and surfaces, each anti-friction member being received between a pair of said laterally spaced bearing surfaces and having cylindrical trunnions received thereby and maintained in substantial contact with said surfaces by the interposition of said cam between said members, said members being free to move in a direction generally longitudinally of said piston toward each other when said cam is not interposed between them.

9. In combination, a piston structure comprising a pair of axially aligned cylindrical end portions and a central portion rigidly interconnecting said end portions, said end portions being of the same diameter and said connecting portion lying substantially completely within an imaginary axial extension of the peripheral surfaces of said end portions, half journal bearings carried by said piston structure and arranged in pairs spaced longitudinally of said piston structure from one another, the bearings of each pair being spaced from one another transversely of

10
5
said piston structure, and the bearings of one pair being arranged with their open sides generally facing the open sides of the bearings of the other pair, integral roller and pin units mounted in said half journal bearings, and cam means interposed between said pairs of bearings and engaged between said rollers whereby to maintain the pins thereof in working engagement with their corresponding half journal bearings.

10. In combination, a cam, a pair of rollers adapted to roll on the respective opposite faces of said cam, trunnions fixed to each of said rollers and projecting axially from the respective opposite ends thereof, a piston structure, and spaced bearings for the trunnions of each of said rollers carried by said piston structure and receiving said trunnions therein, said bearings being so formed that said trunnions are held in said bearings and said rollers are held in operative relation with respect to said cam only by the intervention of said cam between said rollers.

KARL L. HERRMANN.
